Patented Sept. 26, 1916.

UNITED STATES PATENT OFFICE.

LEWIS H. LANIER, OF CORDELL, OKLAHOMA.

FUSING APPARATUS FOR DENTAL CASTING.

1,199,281.

Specification of Letters Patent. Patented Sept. 26, 1916.

Application filed January 22, 1916. Serial No. 73,666.

To all whom it may concern:

Be it known that I, LEWIS H. LANIER, a citizen of the United States, residing at Cordell, in the county of Washita and State 5 of Oklahoma, have invented certain new and useful Improvements in Fusing Apparatus for Dental Casting, of which the following is a specification, reference being had to the accompanying drawings.

10 This invention relates to devices for fusing or casting, and particularly to means for fusing gold or other metals and casting dental inlays.

In casting dental inlays or other like work to-day, an investment cup is used within which the casting is made, the molten metal being forced into the investment cup through the sprue hole thereof either by the action of a vacuum or by the action of centrifugal force. A button of gold or other metal is placed upon the top of the investment and then melted by means of a blow pipe, as for instance, an acetylene blow pipe, a gasolene blow pipe, or an oxyhydrogen blow pipe. The gasolene blow pipe gives a temperature of about 3000 degrees Fahrenheit. The oxyhydrogen and acetylene blow pipes give a temperature of approximately 4000 degrees Fahrenheit. This temperature 25 is not sufficient to secure the very best results in casting or refining, and it is the main object of my invention to provide means whereby the gold or other metal may be submitted to the action of an electric arc 30 which will give a temperature of 5300 degrees Fahrenheit, thus securing a much better fusing of the metal, rendering it more liquid and therefore putting it in better condition for successful casting.

40 Another object of my invention is the provision of means for this purpose which may be used either with a centrifugal casting machine or with a vacuum casting machine, or by direct pressure as on "hinge" 45 machines.

Still another object of the invention is to provide a mechanism of this character including a carbon electrode adapted to be manipulated by the hand and brought into 50 adjacency with the button in order to fuse the latter and a rheostat whereby the amount of current passing through the electrode may be controlled.

55 Still another object is to provide means whereby the melting devices, as before

stated, may be operatively connected to a centrifugal casting machine of the ordinary type.

Other objects will be disclosed in the accompanying specification.

My invention is illustrated in the accompanying drawings, wherein: Figure 1 is a view showing in section the investment cup, the carbon block and the movable electrode, and in top plan view the rheostat for controlling the current; Fig. 2 is a partially diagrammatic top plan view of a centrifugal casting machine, showing the application of my invention thereto; Fig. 3 is an enlarged partial sectional elevation showing the manner in which the bar 31 is rotated; Fig. 4 is a longitudinal sectional view of the carbon block and the investment cup; Fig. 5 is a section on the line 5—5 of Fig. 4.

I will first describe the construction in connection with an ordinary investment cup such as is used in connection with the Elgin vacuum casting machines or hinge machines, as this is the simplest manner in which my invention may be applied.

Referring to Figs. 1, 2 and 4, 2 designates an investment cup or ring of any ordinary or suitable form adapted to vacuum casting. This investment cup incloses the investment material 3, formed to provide the usual sprue opening 4 leading into the mold cavity 5 formed in any usual or suitable manner. This investment cup under ordinary circumstances is a piece of brass tubing about $\frac{1}{16}$ of an inch thick, $\frac{7}{8}$ inch in diameter, and from $1\frac{1}{2}$ to $2\frac{1}{2}$ inches long. Mounted upon the investment cup is a carbon block 6 which may be made of the same material from which electric light pencils are made, which is formed upon its upper face with a depression 7 having a sprue opening 8 extending through the block, and, when the block is in place upon the investment cup, registering with the sprue opening 4 thereof. Either the block 6 for a portion of its length is cut away to fit over and telescope upon the investment ring, or as illustrated, the investment ring extends beyond the investment 3 and telescopes over the carbon block.

Operating in connection with the carbon block is a rheostat comprising a base 9 which may be made of marble or any other suitable material and which has mounted upon it a rheostat coil 10. This coil is

wound upon a porcelain insulator in turn mounted upon brackets 12 fastened to the base 9, a bolt 13 passing through the brackets and through the coil of the rheostat. One end of the rheostat coil 10 is connected to a binding post 14 on the base and from the rheostat at different points along its length extend the conductors or wires 15 which extend to contacts 16. There are four 10 of these contacts 16 shown with the wires 15 therefrom extending to different points on the rheostat in a manner well understood. Operating in connection with the contacts 16 is a key 17 which is movable into engagement with any one of the contacts 16. This key is electrically connected by any suitable conductor 18 to a binding post 19. The base 9 is also provided with a binding post 20. Engaging the binding posts 14 and 20 are the wires 21 leading from any suitable current supply. Leading from the binding post 19 is a wire 22 which is electrically connected in any suitable manner to the carbon receptacle or block 6. Leading 25 from the binding post 20 is a wire 24 which is connected to a metal core 25 passing through a handle 26 of insulating material. The metallic core 25 is operatively connected to a metallic ferrule 27 and electrically 30 connected to this ferrule 27 and to the core 25 is attached a carbon rod 28. This carbon rod in actual practice is about 6 inches long and approximately one-half inch in diameter and forms an electrode.

35 The operation of this form of my invention will be obvious. When it is desired to perform a casting operation a button of metal, as for instance, gold, is placed in the hollow 7 of the block 6. The current is then 40 turned on and the member 17 adjusted so as to secure the proper strength of current. The electrode 28 is then approximated to the metallic button and an electric arc is formed between the button and the electrode 28 45 which fuses the button. As soon as the button is properly fused, the valve (not shown) which controls the connection of the investment cup with the vacuum chamber of the Elgin mechanism is turned and the 50 molten metal is sucked into the investment cup.

55 In Fig. 2 I have shown my invention as applied in connection with a centrifugal casting machine. All the parts of the rheostat and the electrode 28 and its handle 26 are exactly the same as previously described. Therefore the same reference numerals have been used for these parts. The centrifugal casting apparatus forms no part of my invention as it is old and well known and has 60 only been shown for illustration. It consists of a metallic base 29 upon which is mounted a shaft or pedestal 30, this shaft being mounted in ball bearings and carrying a metallic bar 31 which in the ordinary

form of this apparatus is about one inch wide and twelve inches long and about one-eighth of an inch thick. A spring motor, designated generally 32, is operatively connected to the shaft or pedestal 30 so as to 70 rotate the latter. A latch 33 is designed to hold the shaft against the action of the spring, and when this latch is released the spring will cause the rotation of the shaft 30 and the bar 31. Inasmuch as all of these 75 details are old and well known it is not necessary to describe them further.

80 Mounted upon one end of the bar 31 is a sliding weight 34 which may be shifted along the bar and held in its adjusted position by means of a set screw. The opposite end of the bar 31 carries upon it the metallic sleeve 35 which is cut away upon its upper face as at 36 and which is held to the bar in any suitable manner. This metallic 85 sleeve 35 is designed to support the carbon receptacle and the investment cup. The investment cup is of the form previously described and is designated 35 in Fig. 4. The carbon receptacle consists of a block of 90 carbon 36 which is about 4 inches long and 1 inch in diameter. At one end the carbon block is so formed as to telescopically engage with the investment ring and at this end the carbon block is formed with a vertically disposed slot or groove 37 about $\frac{3}{8}$ of an inch wide and $\frac{1}{2}$ of an inch deep which extends inward from the end of the block which confronts the investment and intersecting this groove 37 is a depression 38 having the form of a half moon. This depression is 1 inch wide and is cut in the side of the carbon block or receptacle and extends nearly to the bottom of the groove 37. The crescent shape of the depression 38 permits 100 the operator to use the carbon pencil or electrode 28 to the best advantage in fusing gold. The end of the investment which confronts the groove 37 is made concave so that the molten metal will be directed toward 105 the sprue opening 39 and allow no scattering of the molten metal.

110 With the construction as above described, a button of gold or other metal is placed within the depression 38 and the carbon pencil or electrode 28 is brought into proximity thereto and the current turned on. An electric arc will thus be formed between the electrode and the button which will cause the melting of the button at a very 115 high temperature. As soon as the metal has been liquefied to the proper degree the carbon pencil is withdrawn and the latch 33 is released, whereupon the spring motor will cause the bar 31 to rotate at a high 120 velocity and the centrifugal force will cause the gold or other molten metal to be forced outward and into the mold cavity in the investment through groove 37.

125 The particular form of centrifugal ma-

chine used is immaterial, and it is obvious that the invention may be adapted to any desired form of centrifugal casting machine. The details of this machine form no part of my invention. The important elements of my invention are the carbon melting block which forms one electrode, the high resistance pencil or rod which forms the other electrode and which may be brought into proximity to the metallic button, and the means for controlling the amount of current passing through the circuit. These three elements may be used in a large variety of forms and with a large variety of apparatus, and the forms which I have shown are merely illustrative of two applications of my invention.

It will of course be understood that the investment with its sprue opening constitutes a casting flask as used in conjunction with my improved means for melting the metal to be cast within the flask.

The apparatus previously described is particularly useful as a substitute in dental offices for the gasoline blow pipe and the acetylene and oxyhydrogen blow pipes. The objections to the gasoline blow pipe are many. It is relatively too slow in its action to secure good casting as it requires from five to thirty minutes to complete the operation of casting by a gasoline blow pipe. It will not heat gold sufficiently to cast into cold investment and do accurate work. Casting in a cold investment is advocated by the dental profession to-day as thus the minimum amount of contraction or expansion is caused in the investment. Furthermore, the gasoline blow pipe cannot fuse or refine platinum or iridium. There is, of course, constant danger of fire from leakage of the gasoline. In use, a gasoline blow pipe is very dirty to handle and there is considerable odor.

While the acetylene and oxyhydrogen blow pipes give sufficient heat to fuse gold and do good casting, they are much slower than electricity in doing the work. Furthermore, the expense of installation and operation is very large, and they create a disagreeable odor and this is particularly true of the acetylene blow pipe. Furthermore, there is constant danger of explosion and they require considerable space to install and operate. Neither the acetylene or the oxyhydrogen blow pipe will fuse platinum or iridium to a degree sufficient for the casting operation. By using the electric arc for fusing metals the casting of metal is very much facilitated, and in actual operation it only takes from two to five seconds to complete the casting, thus saving from five to thirty minutes at each casting operation. The gold or other precious metals are heated almost instantly to a degree almost sufficient that they may be cast in a

cold investment. Platinum or iridium may be refined or cast in the same manner as gold.

The device is cheap to install and operate; the cost of operation is very slight; and it takes up very little space and it is particularly clean. It is advisable to use the rheostat in my apparatus because by its means various degrees of heat may be attained, which is requisite because of the different amounts and fusing points of the metals that may be used. Where only a small quantity of metal is to be fused, less current is necessary than with larger amounts.

All of the investment compounds used in dental casting contain a little iron. Hence when molten metal is cast, it is slightly contaminated by the iron, and about three casts with one piece of gold is all that should be made until the gold is refined. This takes from five to thirty minutes of hard work and some expense. With my electrical casting apparatus the heat is sufficient to burn out this iron at each casting operation which eliminates these periods of refining. While the fusing point of iron is higher than that of gold, yet the specific gravity of gold is approximately $19\frac{1}{2}$ and that of iron $7\frac{1}{2}$ and hence the lighter metal will rise to the surface of the molten mass and consequently burn out first. It will be noted that the heat is communicated to the investment material by reason of the intimate contact between the investment material and the carbon block or electrode and between said carbon block or electrode and investment ring, thus heating the investment and at the same time providing means for melting the precious metal.

Having thus described my invention, what I claim is:

1. The combination with an investment ring comprising a cylindrical metallic body having an approximately uniform diameter and open at its opposite ends and investment material disposed in the ring, of a carbon block having removable sliding engagement with one end of the ring and fitting in close contact with the investment material, the investment material and the carbon block having a sprue passage and the carbon block being hollowed out on one face to provide a depression for the reception of metal to be fused, a relatively movable electrode of high resistance material and having a non-conductive handle, and electrical connections between the carbon block of high resistance material and a source of current and between the movable electrode and said source.

2. In a dental casting apparatus the combination with a rotatably mounted bar, means for rotating the bar, a latch detachably holding the bar from rotation, and a

4
metallic sleeve mounted upon the bar and
cut away upon its upper face, of an invest-
ment ring insertible into said sleeve, invest-
ment material disposed within the ring and
5 constituting a flask having a sprue opening,
a body of high resistance material consti-
tuting an electrode and removably support-
ed in said sleeve in contact with the invest-
ment material and the ring, said body hav-
10 ing a longitudinally extending recess in its
upper face adapted to receive the material to
be melted and having a longitudinal chan-
nel communicating with the sprue opening

of the investment, a rod of high resistance
material constituting a movable electrode
and adapted to be brought into contiguity
with the material in said recess of the block,
and electrical connections between the rod
and the source of current and between said
block and the source of current.

15 In testimony whereof I hereunto affix my
signature in the presence of two witnesses.

26 LEWIS H. LANIER.
